Atty.

UNITED STATES PATENT OFFICE.

CHARLES HEYER, OF RACINE, WISCONSIN.

IMPROVEMENT IN APPARATUS FOR TURNING THE LEAVES OF MUSIC.

Specification forming part of Letters Patent No. 118,935, dated September 12, 1871.

To all whom it may concern:

Be it known that I, CHARLES HEYER, of Racine, in the county of Racine and in the State of Wisconsin, have invented certain new and useful Improvements in Device for Turning Music; and do hereby declare that the following is a full, clear, and exact description thereof, reference being had to the accompanying drawing and to the letters of reference marked thereon making a part of this specification.

The nature of my invention consists in the construction and arrangement of a device or apparatus for turning sheet-music, as will be herein-after more fully set forth.

In order to enable others skilled in the art to which my invention appertains to make and use the same, I will now proceed to describe its construction and operation, referring to the annexed drawing, in which—

Figure 1 is a side view of the machine set up for use. Fig. 2 is an end view of the same. Fig. 3 is a section of the revolving drum, showing the journal upon which the weighted rope acts; and Fig. 4 is an edge view of the portfolio or cover in which the music is placed.

A represents a stand of any suitable size and construction. From this stand or bed rise two standards, B B, in which the journals of a drum, C, have their bearings, one of said journals, a, having a rope or cord, b, attached to it. This cord passes up over a pulley, D, arranged in an arm from an upright post, E, and from said pulley the cord passes down through a tube or cylinder, H, and to the end of the cord is attached a weight, G. In other two standards, B' B', rising from the bed A, is hung a frame, I, on pivots in its sides, so that it can swing back and forth. Rubber bands or springs d d are attached to the lower end of the frame I and operating in opposite directions, so that when the frame is swung to either side said bands or springs will bring the frame back in a vertical or almost vertical position. In the frame I is a slide, J, which moves up and down in the same and is held upward by means of rubber bands or springs e e, and a cord, f, connects the lower end of said slide with a treadle, K. This treadle is provided with springs h to hold it up.

This machine is set a suitable distance from the

music-stand, say so that the frame I will be about fifty inches to the left of the upper right-hand corner of the music. The music is placed in a portfolio or cover, L, provided with hooks k k, as shown in Fig. 4, the first and last sheets being held by said hooks while the intervening sheets are loose. To the drum C is attached a cord, m, provided at regular intervals with spring-catches i i. When this cord is wound around the drum the cord b will be entirely free from the journal a, or not around the journal. The cord m is then passed through a hole, n, in the frame I, and drawn out, thus unwinding it from the drum and at the same time winding the cord b on the journal a. The slide J holds each spring-catch i from passing through the hole n until the slide is lowered by the treadle K, and thus it will be seen that the weight G operating through the cord b on the journal of the drum will revolve the same and wind up the cord m whenever the slide J is lowered to allow the passage of the spring-catches i i. These catches are placed on the upper right corner of the music-sheets not held by the hooks k k, and the treadle being arranged in any suitable manner so that it can be touched or operated either by hand or foot, it follows that whenever desired to turn one sheet it is only necessary to press down the treadle for an instant to allow the preceding catch i to pass through the hole n, when the drum C turns or revolves, winding up the cord turning the sheet. The catch on this sheet releases itself when brought over to the left, and stops at the hole n until desired to turn the next sheet in the same manner. The frame I, swinging on pivots and provided with the openings d d, prevents breaking of the cord m or sudden jar to the device. The slack cord or thread between the catches i i is laid in between the sheets of music.

Having thusfully described my invention, what I claim as new, and desire to secure by Letters Patent, is—

1. The drum C, with journal a, cord b, weight G, pulley D, and tube H, all constructed and arranged substantially as and for the purposes herein set forth.
2. The swinging frame I, provided with hole n, slide J, and springs d d and e, all substantially as and for the purposes herein set forth.

3. The cord *m* with spring-catches *i i* attached to the drum *C*, and operating substantially as and for the purposes herein set forth.

4. The combination of the drum *C*, cord *b*, weight *G*, swinging frame *I* with the slide *J*, and the cord *m* with the spring-catches *i i*, all constructed and arranged to operate substantially as and for the purposes herein set forth.

In testimony that I claim the foregoing I have hereunto set my hand this 24th day of April, 1871.

CHARLES HEYER.
